UNITED STATES PATENT OFFICE.

STALEY DANE POOLE, OF MOLINE, ILLINOIS, ASSIGNEE TO DEERE & COMPANY, A CORPORATION OF ILLINOIS.

CULTIVATOR.

1,140,767.

Specification of Letters Patent. Patented May 25, 1915.

Application filed March 30, 1909. Serial No. 486,780.

To all whom it may concern:

Be it known that I, STALEY DANE POOLE, a citizen of the United States, residing at Moline, in the county of Rock Island and State of Illinois, have invented certain new and useful Improvements in Cultivators, of which the following is a specification, reference being had therein to the accompanying drawing.

This invention relates to improvements in cultivators.

The novel features of construction and arrangement can be employed in earth working tools of any of a number of styles of this general class. The matters of improvement, however, are particularly well adapted for use in cultivators of the sort employed in cultivating orchards.

The object of the invention is to provide a construction in which the tool-carrying element shall be adjustable independently of the supporting and transporting element; in which the heavier work of lifting and adjusting the tools can be accomplished by the force of the draft, or, when desired, by a minimum of manual labor, by which several transverse rows of tools can be held uniformly in relation to the ground surface; and which shall have its parts so related that the active elements can be projected laterally beyond the supporting elements, for purposes to be set forth.

Figure 1 is a plan view of a cultivating mechanism embodying my improvements. Fig. 2 is a side elevation of the same. Fig. 3 is a rear elevation. Fig. 4 is a detail view showing in side elevation steering devices of a different kind than are shown in Figs. 1 and 2. Fig. 5 is a plan view showing the machine with the tool frame fitted with the detachable lateral extensions.

1 is an axle upon which are mounted the wheels 2, 2.

3, 3 indicate upright bars which are carried upward a sufficient distance to conveniently support a driver's seat and which may be formed of one length of metal suitably bent. At their lower ends they are supported upon the axle 1 by means of 50 clips 4, 4. From the bars 3, 3 there extend

horizontal bars 5, 5, which are bent inward at 6, 6, and at their front ends are secured to a vertical casting or bearing piece 7.

8, 8 are uprights or vertical bars which are secured to the bars 5, 5 and extend downward therefrom to a long horizontal cross-bar 9. This bar is at its ends connected to the axle by horizontal arms 10, 10, these being secured to brackets or clips 11 at their rear ends.

12 is a brace bar or tie-bar interposed between the top bars 5, 5 and secured thereto.

The working frame, or frame which carries the tools, is constructed as follows: 13 is a long rear cross-bar connected to forwardly extending bars 14, 14, the latter having their front parts 15 converged or bent inward toward the central longitudinal plane. Preferably the cross-bar 13 and the longitudinally arranged bars 14, 15, are all 70 formed from a single bar of metal suitably shaped by bending. 16, 16 are longitudinally arranged bars which at their front ends are flanged, and bolted, as at 17, to the bars 15. At their rear ends they are flanged 75 and secured at 18 to the cross bar 13. 19 are cross bars interposed between the side bars 14 and the intermediate bars 16. Tool supporting bars 21, of any suitable number, are arranged longitudinally in the working 80 frame. By suitably bending the bars, as shown at 13^a, one can be utilized to support more than a single tool and hold one tool out of the longitudinal line of another. Bars 16 are also utilized to support tools, as shown 85 in the drawings.

The parts of the longitudinal bars which carry the tools are so spaced in relation to each other that the wheels can be placed either close together or farther apart, as may 90 be desired. Thus in Fig. 1 and others, the wheels are shown relatively close together, each being situated between one of the bars 16 and bar 21; whereas in Fig. 5 the wheels are mounted at other points on the axle, in 95 the spaces between the outer bars 14 and the next adjacent longitudinal bars 21. In either case the wheels are surrounded, horizontally by frame work adapted to carry, on its laterally projecting parts, tools in longi- 100

tudinal planes outside of the wheel plane, as well as carry tools between the wheels.

The other parts of the working frame or

- 5 tool frame consist of two similar frame sections each of which has a rear bar 13^b and a forwardly extending bar 14^a. The bar 13^b of this frame is bolted at 13^c to the bar 13, and the arm or bar 14^a is suitably secured at its forward end to the frame. Each of these
10 frame sections is provided with one or more tools. When a wide strip of earth is to be covered by the machine the entire working frame structure can be employed, that is, the larger central part and the two end sections.
15 But under many circumstances it is found that but one of them need be present, and at such times the other can be removed. It will be seen that with a provision of this character taken in connection with the provision for changing the position of the wheels, there is a wide range in respect to the extent to which a tool carrier can be projected laterally beyond either of the wheels.
20 22, 22 are bars diverging and extending backward from the casting 7, to which they are secured at their front ends. At their rear ends they are secured to the cross bar 9 of the supporting wheel frame. A front 30 supporting and steering device is provided consisting of the caster wheel 23, its yoke carrier 24 and vertical spindle 25. The spindle is mounted in the tubular bracket casting 7.
25 The working frame that has been above described is supported on and carried by the wheel frame, but is movably connected thereto. At each side of the machine there are two parallel link bars 26, 27, each pivotally connected at one end to a side bar of the wheel frame, and pivotally connected at the other end to a side bar of the tool frame or working frame 14. The pivotal attachments for these links consist of plates or
35 lugs 28 which are rigidly fastened to the side bars of the frames. At the front end of the working frame there is a forward projecting frame extension 30. 32 indicates a strap frame extending forward and downward from the upper end of the spindle 25, to which it is pivotally attached, and it carries a loop 33 through which passes the bar or draft link 31, the latter being secured by a vertical pivot to the frame extension 30
45 and being capable of moving longitudinally, to a limited extent, forward and backward through the loop. With this construction, the lateral swinging of the link 31 under the action of the draft is transmitted to the strap frame 32 which is thus caused to turn the spindle 25 of the steering wheel 23 so as to guide the machine. These steering devices also are adapted to permit the tool frame to rise and fall freely for the strap frame 32 swings forward and upward in
50

unison with the tool frame as it is moved upward and forward on the parallel links 26, 27.

When the machine is to be used on hilly ground, I prefer to do the steering by means of a pole or tongue 41 such as shown in Figs. 1 and 2, it being possible with the tongue to keep the machine from running onto the heels of the horses. A seat 34 for the driver is mounted on the upright frame part 3. 75 To enable the driver when in his seat to adjust the working or tool frame up and down and to lock it in adjusted position the following devices are provided. 36 is a transverse rock shaft mounted on the frame bars 5, 5 and carrying at its ends crank arms 35¹ which are connected by means of links 37, 37 with the tool frame. 35 is a hand lever connected to one of the crank arms 35¹ or to the shaft 36 and provided with a locking device 39 which co-operates with the notched segment 38. By swinging the hand lever 35, the tool frame can be raised and lowered in horizontal parallelism and locked in the desired position. By providing the double 90 crank arm and link connection, both sides of the tool frame are very firmly supported so that the tendency for one side of the frame to be drawn deeper than the other is thoroughly overcome. Such a tendency is especially noticeable when only one of the side extensions of the tool frame is employed.

The tools are secured to the adjustable frame in such manner that they lie some on one transverse line, and some on other lines, that is to say, a set of tools is relatively farther forward, and another set or other sets, are relatively farther backward. When the tool frame is constructed and related and connected to the wheel frame in the manner described, the sets of tools are all kept in predetermined positions relative to each other and to the surface of the ground. The parallel link bars 26, 27, insure that the front tools shall rise and fall in horizontal parallelism with the rear ones, and variation in the depth of cutting is avoided.

The wheels are secured in place longitudinally of the axle by means of collars 40, which are adapted to be secured to the axle 118 at either of several places along it. At times it is desirable to have the wheels close together and equally distant respectively from the adjacent ends of the tool frames, as shown by broken lines in Fig. 1; at others it is preferable to have them respectively near the side bars though equi-distant therefrom; while in still other cases it is desirable to have both wheels relatively nearer one end of the frame than the other, that is to say, to have a considerable part of the frame project at one side some distance beyond the adjacent wheel, while the opposite wheel is situated near its side bar. Each of these relative positions can be quickly secured in the 120

present construction, as it is only necessary to withdraw the removable cotters which secure the axle 1 in the holders at 11, and also the cotters from the set collars 40 for the wheel hubs, after which the collars can be reset at different places to hold the wheels in any of the above described relative positions.

A mechanism such as herein shown is particularly well adapted for cultivating orchards or plots of ground where bushes or trees are growing, especially trees with branches relatively close to the ground.

The tool frame can be caused to project more or less at each end, and at the same time uniformly at the two ends, beyond the wheels, so that the projecting ends can carry the tools along the surface of the ground close in toward the tree trunks and under their branches; or the frame can be caused to project to a still greater extent at one end in order that the tools at that end may extend farther under overhanging parts, the draft mechanism, and the driver's support being at all times in vertical planes outside of such overhanging bodies. The construction of the parts of the two frames which I have described enables me to keep the operative parts in low horizontal planes and provide a mechanism of great strength. The draft is transmitted directly to the tool frame, the wheel frame constituting merely a supporting and carrying structure. The tools can be of any of the several sorts used on machines of this general class, ordinary cultivator hoes, or the wider scraping shovels, or the plowlike tools that are frequently used. The draft of the team being applied in the way described it can be utilized to lift the frame and tools out of the ground, such lifting by the power of the draft commencing as soon as the operator releases the detent 39 from the segment 38.

By means of the lever and its lock, the tool frame and the tools can be fastened rigidly in any working position, vertically, that may be desired. With a machine constructed in the way described the shovels can be held at a predetermined uniform depth and be prevented from entering the ground at one side of the machine more deeply than at the other, even when the wheels are so placed in relation to the frames that the tool frame overhangs at one end or extends considerably farther beyond the adjacent wheels than it extends at the other end beyond the opposite wheel. The shovels at the overhanging or projecting end are prevented from sinking beyond the depth desired, which is uniform for all the tools.

It will be seen that I provide a main frame which is held uniformly at all times in relation to the surface of the ground; secondly, a vertically movable tool frame

which is held positively, after adjustment, and being locked, against movement upward or movement downward around any transverse axis, either bodily, as an entirety, or at either end, and is maintained positively in parallelism to the main frame and to the ground, and, third, a horizontally vibratable frame or support (the yoke 24 and spindle 25) which is vibratable horizontally relatively to the other two frames, but not movable, in ordinary use vertically in relation to the main frame. For certain kinds of cultivation a mechanism of this sort is much more advantageous than are those wherein the frame elements (including those mounted directly on the ground wheels, and those which are connected to the tool) are so arranged that they can rock around the axis of the wheels when at work. The rear ground wheels in the present machine are fixed on transverse lines while the front wheel, as aforesaid, is adapted to swing laterally, and although connected to the main frame it is indirectly connected to the draft devices in such way that the forward force of the draft is practically all taken, primarily, by the tool frame, the transmission of draft force to the main frame being effected through the tool frame.

What I claim is:

1. In a cultivator, the combination of the framework, rear supporting wheels, a front supporting and steering wheel, a vibratable carrier for the steering wheel journaled in the framework on an upright axis, a laterally swinging draft link pivoted to the framework independently of the steering wheel and its vibratable carrier so that the force of the draft is applied independently of the steering wheel and its carrier, and connections between the draft link and the said vibratable carrier for transmitting to the latter the swinging movements of the link to steer the machine.

2. In a cultivator, the combination of a supporting frame, rear ground wheels and a front steering wheel on which said frame rests, an upright spindle upon which the steering wheel is mounted, a tool frame adapted to be bodily raised and lowered relative to the supporting frame, a draft link connected to the tool frame by an upright pivot to permit the link to swing laterally, and an arm connected to the steering wheel spindle and loosely connected to the draft link whereby the wheel is turned by the swinging of the draft link.

3. In a cultivator, the combination of a supporting frame, rear supporting wheels and a front steering wheel upon which the frame rests, an upright spindle upon which the steering wheel is mounted, a tool frame arranged above the supporting frame, means connecting the tool frame and supporting frame comprising parallel link

- bars arranged to extend downward and forward from the tool frame to the supporting frame, a laterally swinging draft link connected to the tool frame, and an arm pivoted 5 on a horizontal axis to the steering wheel spindle at its upper end and extending downwardly and forwardly and connected at its lower end with the draft link, substantially as set forth.
- 10 4. In a cultivator, the combination of a main frame, means for holding the main frame at all times in fixed relation to the surface of the ground comprising supporting wheels for the rear part of the frame 15 and a supporting and steering wheel for the front part of the frame, a horizontally vibratable frame in which the said steering wheel is mounted, a vertically movable tool frame mounted on the main frame and held 20 positively in parallelism to the main frame and the ground, laterally swinging draft devices connected directly to the tool frame and adapted to apply the force of the draft thereto independently of the steering wheel 25 frame, and means for transmitting the swinging movement of the draft devices to the steering wheel frame.
5. In a cultivator, the combination of a main frame, supporting wheels arranged to 30 maintain the main frame at all times in fixed relation to the ground surface, a vertically movable tool frame carried by the main frame, connections between the tool frame and the main frame adapted to hold 35 the former positively in parallelism to the main frame and to the ground, and draft devices connected directly to the tool frame, the connections between the tool frame and the main frame being constructed and ar- 40 ranged to cause the force of the draft to lift the tool frame when the latter is freed for adjustment.
6. In a cultivator, the combination of a main frame, supporting wheels arranged to 45 maintain the main frame at all times in fixed relation to the ground surface, a vertically movable tool frame carried by the main frame, means connecting the tool frame and the main frame comprising a 50 plurality of links connected at their rear ends to the tool frame and at their front ends to the main frame, and draft devices so connected to the main frame that the force of the draft acts, when the tool frame 55 is freed for adjustment, to swing the rear ends of the said links upward and lift the tool frame.
7. In a cultivator, the combination of a main frame, means for holding the main 60 frame at all times in fixed relation to the ground surface comprising a pair of sup- porting wheels mounted on fixed axes at the rear part of the main frame, and a support- ing and steering wheel at the front part of
- said frame, a vertically movable tool frame 65 mounted on the main frame above the axis of the rear supporting wheels, connections between the tool frame and the main frame adapted to hold the tool frame positively in parallelism to the main frame and the 70 ground, and draft devices connected directly to the tool frame, the connections between the tool frame and the main frame being constructed and arranged so that the force of the draft is adapted to lift the tool frame 75 when it is freed for adjustment.
8. In a cultivator, the combination of a main frame, an axle extending across the rear part of said frame, a pair of support- 80 ing wheels on said axle, a supporting and steering wheel for the front part of the main frame, a vertically movable tool frame disposed above said axle, means comprising a plurality of links interposed between the tool frame and the main frame and adapted 85 to hold the tool frame positively in parallelism to the main frame and ground, and draft devices connected directly to the tool frame, the said parallel links being so dis- posed that the force of the draft acts to lift 90 the tool frame when it is freed for adjust- ment.
9. In a cultivator, the combination of a main frame, an axle extending across the rear part of said frame, a pair of support- 95 ing wheels on said axle, a supporting and steering wheel for the front part of the main frame, a vertically movable tool frame disposed above said axle, means comprising a plurality of links interposed between the tool frame and the main frame and adapted 100 to hold the tool frame positively in parallelism to the main frame and ground, and draft devices connected directly to the tool frame, the said parallel links being so dis- posed that the force of the draft acts to lift 105 the tool frame when it is freed for adjust- ment.
10. In a cultivator, the combination of a main frame, an axle extending across the rear part of said frame, a pair of supporting wheels on said axle, a supporting and steer- 110 ing wheel for the front part of the main frame, a vertically movable tool frame disposed above said axle and having a plurality of tools disposed some in front and some to the rear of the said axle, means comprising a plurality of links interposed between the tool frame and the main frame and adapted 115 to hold the tool frame positively in parallelism to the main frame and ground, and manual means for raising and lowering the tool frame.
11. In a cultivator, the combination of a main frame, an axle extending across the rear part of the said frame, a pair of sup- porting wheels on said axle, a supporting 120 and steering wheel for the front part of the main frame, a vertically movable tool frame disposed above said axle and having a plu- 125 rality of tools of which some are arranged

on transverse lines in front of said axle both inside and outside of the wheels thereon and others are arranged on transverse lines to the rear of the said axle both inside and outside of the wheels thereon, means comprising a plurality of links interposed between the tool frame and the main frame and adapted to hold the tool frame positively in parallelism to the main frame and ground,

and manual means for raising and lowering the tool frame.

In testimony whereof I affix my signature, in presence of two witnesses.

STALEY DANE POOLE.
